WAVE-SIGNAL TRANSLATING CHANNEL

Nelson P. Case, Great Neck, N. Y., assignor to
Hazeltine Corporation, a corporation of Delaware

Application May 8, 1942, Serial No. 442,158

10 Claims. (Cl. 178—44)

The present invention relates to wave-signal translating channels and, particularly, to such channels of the type adapted to translate wave signals selectively in either direction through the channel. While the invention is of general application, it is particularly suited for use in coupling an antenna-ground system to a wave-signal apparatus adapted both to transmit and receive wave signals.

In many instances, it is desirable to translate wave signals selectively in either direction through a wave-signal translating channel. For example, a rather simple form of portable wave-signal apparatus for two-way communication utilizes an oscillator in common to both transmitting and receiving apparatus. This oscillator is coupled to an antenna-ground system and is used in conventional manner for transmitting, but is also used as a super-regenerative detector for deriving the modulation components of a received wave signal. In this arrangement, the super-regenerative type of detector provided by the oscillator has exceptionally high sensitivity as is well known, but there is the disadvantage that the generation of oscillations during the normal operation of such detector results, unless prevented, in undesired radiation of wave-signal energy which interferes with other receivers operating on the same frequency and located within a radius of perhaps several miles from the receiver employing the superregenerative form of detector. To avoid this disadvantage of the superregenerative type of detector, it is customary to isolate the detector from the antenna-ground system by the use of a buffer amplifier stage which couples the antenna system to the detector. However, in the two-way communication apparatus previously referred to, it was pointed out that the oscillator is used not only as a superregenerative detector but also as an oscillator for generating wave signals for purposes of transmission. In such case, one can no longer use a simple buffer amplifier stage for the purpose described but must use a two-way wave-signal translating channel by which wave signals may be translated through the channel in one direction during transmission and in the opposite direction during reception.

In an arrangement of the type just described, a two-way wave-signal translating channel might simply comprise two amplifier stages coupled in parallel but in opposite senses between the antenna system and the wave-signal communication apparatus and adapted, upon selective energization of the amplifiers, to translate wave signals in opposite directions. Such an arrangement,

however, is not a complete solution to the problem since the amplifier vacuum tubes have internal capacitances which tend to cause undesired translation of wave-signal energy in a direction opposite to the desired direction. It would be desirable, therefore, to provide in an arrangement of the type described, a two-way wave-signal translating channel of simple circuit arrangement involving a minimum of circuit components and yet one which possesses a high degree of freedom from undesired translation of wave signals in a direction opposite to a desired direction.

It is an object of the present invention, therefore, to provide a new and improved wave-signal translating channel adapted to translate wave signals selectively in either direction through the channel.

It is a further object of the invention to provide a new and improved wave-signal translating channel of the type described and one having substantially complete freedom from undesired translation of wave signals through the channel in a direction opposite to a selected direction.

It is an additional object of the invention to provide a wave-signal translating channel of the type described wherein certain of the circuit components perform their usual functions when wave signals are translated in one direction through the channel but perform other and totally unrelated functions when the translation of wave signals through the channel occurs in the opposite direction, thus providing a wave-signal translating channel of simplified and improved circuit arrangement involving a minimum of circuit components.

In accordance with the invention, a wave-signal translating channel comprises a pair of terminal circuits for the channel, a pair of vacuum-tube repeater devices, and means for coupling the devices between the terminal circuits to effect translation of wave signals between the terminal circuits in one direction through one of the devices and in an opposite direction through the other of the devices. Each of the devices and its associated coupling means have undesirable reactance tending to produce undesirable translation of wave signals between the terminal circuits in a direction opposite to its direction of normal translation. The translating channel includes means for selectively energizing the repeater devices to effect translation of wave signals in a selected direction between the terminal circuits, and means for reducing the tendency of a selected device undesirably to translate wave

signals in the direction opposite to the selected direction comprising means including the undesirable reactance of the nonselected one of the devices and its associated coupling means for neutralizing the undesirable reactance of the selected device and its associated coupling means.

For a better understanding of the present invention, together with other and further objects thereof, reference is had to the following description taken in connection with the accompanying drawing, and its scope will be pointed out in the appended claims.

Referring now to the drawing, the single figure thereof is a circuit diagram, partly schematic, of a complete two-way communication wave-signal apparatus embodying the present invention in a preferred form.

Referring now more particularly to the drawing, the wave-signal apparatus in general includes an antenna-ground system 10, 11 having an adjustable condenser 12 and an inductor 13 included in series therein for tuning the antenna-ground system to a predetermined operating frequency. The antenna-ground system is connected to a terminal circuit comprising terminals 14, 15 of a wave-signal translating channel 16, more fully described hereinafter. The translating channel 16 includes a second terminal circuit comprising terminals 17, 18 which are connected to terminals 19, 20 of a two-way wave-signal communication apparatus 21. The latter in its simplest form includes an oscillator which is used to generate a wave signal for transmission and is also used as a superregenerative detector to derive the modulation components of a received wave signal. The two functions of the oscillator are controlled by a manually-adjustable transmit-receive switch 22. In the transmit position T of switch 22, a microphone 23 is coupled through suitable amplifiers and a modulator stage to the oscillator of unit 21 to modulate the wave signal generated thereby in accordance with a speed signal to be transmitted. In the receive position R of switch 22, the output of the superregenerative detector is coupled through one or more stages of audio-frequency amplification to a sound reproducer, for example a loudspeaker 24.

It will be understood that the various units just described may, with the exception of the signal-translating channel 16, be of a conventional construction and operation, the details of which are well known in the art, rendering detailed description thereof unnecessary. Considering briefly the operation of the wave-signal apparatus as a whole, and neglecting for the moment the operation of the signal-translating channel 16 presently to be described, upon operation of the switch 22 to the transmit position T, wave signals are generated by the oscillator of unit 21 and, after modulation by a speech signal derived from the microphone 23, are translated through the signal-translating channel 16 to the antenna-ground system 10, 11 for radiation thereby. Upon operation of the switch 22 to the receive position R, wave signals received by the antenna-ground system 10, 11 are translated through the wave-signal translating channel 16 to the apparatus 21 where the oscillator of this unit, now operating as a superregenerative detector, derives the modulation components of the received wave signal. The modulation components are amplified by the amplifier stages of unit 21 and are applied to the sound reproducer 24 for reproduction in a conventional manner.

Referring now more particularly to the portion of the system embodying the present invention, the wave-signal translating channel 16 comprises a pair of terminal circuits 25, 26. The 5 terminal circuit 25 includes a winding 27 connected to the terminals 14, 15 and a winding 28 inductively coupled to the winding 27 and tunable by a condenser 29 to the frequency of the wave signals to be translated by the channel 16. The terminal circuit 26 similarly includes a winding 30, connected to the terminals 17, 18 and tunable by a condenser 31 to the selected operating frequency or frequency of the wave signals to be translated by the channel 16, 15 and a winding 32 inductively coupled to the winding 30 and tapped at a point P to provide a winding section 32a on one side of tap P and a winding section 32b on the other side of said tap. The translating channel also includes a 20 pair of vacuum-tube repeater devices 33, 34 each including input and output electrodes. Specifically, the repeater device 33 includes input electrodes comprising a control electrode 35 and a cathode or filament 36, the latter being energized from an energizing source indicated as +A through a cathode circuit including a first contact R of a switch 37. This repeater device also includes output electrodes comprising an anode 38 and the cathode 36. The corresponding electrodes of the repeater device 34 are indicated by the same reference numerals primed, the cathode 36' of this device being connected to a second switch contact T of the switch 37 to be selectively energized from the source +A. The switch 37 30 thus comprises means for selectively energizing the repeater devices 33, 34, specifically for energizing the cathode circuits of the repeater devices, to effect translation of wave signals in a selected direction between the terminal circuits 40 25 and 26.

The translating channel 16 includes means for coupling the vacuum-tube repeater devices 33, 34 between the terminal circuits 25 and 26 to effect translation of wave signals between the 45 terminal circuits in one direction through one of the devices and in an opposite direction through the other of the devices. This means comprises a condenser 39 and grid resistor 45 for coupling the input electrodes 35, 36 of the repeater device 33 to the terminal circuit 25, and a similar condenser 40 and grid resistor 46, together with a condenser 44, for coupling the input electrodes 35', 36' of the repeater device 34 to the terminal circuit 26 and particularly to the section 32a of the winding 32 lying above the tap P. The last-named means also includes a connection of the anode 38 of vacuum tube 33 through the section 32b of the winding 32 of terminal circuit 26 to a source of space current indicated as +B, and includes a similar connection of the anode 38' of the repeater device 34 through the winding 28 of the terminal circuit 25 to a source of space current indicated as +B'.

The switch 37 preferably is connected for uni-control operation with the switch 22 of unit 21 as indicated by the broken line 41.

In considering the operation of the wave-signal translating channel just described, assume that it is desired to receive wave signals and to translate such received wave signals from the antenna-ground system 10, 11 through the translating channel 16 to the receiving apparatus of unit 21. In this case, the switch 22 of unit 21 is moved to the receive position R, thus simultaneously moving the switch 37 to close its contact R

and selectively energizing the cathode circuit of the vacuum-tube repeater device 33. The latter thereupon operates in conventional manner as a repeater device to translate wave signals, applied from the antenna-ground system 10, 11 and the terminal circuit 25 to the terminal circuit 26 and thus to the circuit terminals 19, 20 of the unit 21, the control electrode 35 developing across the resistor 45 a self-bias potential by peak rectification of the applied wave signals.

However, the oscillator of unit 21 is used during reception as a superregenerative detector and the oscillations generated thereby are applied to the terminal circuit 26 and hence through the section 32b of winding 32 to the anode 38 of the repeater device 33. Now it is well known that there is a certain amount of undesirable capacitive reactance caused by the inherent interelectrode capacitance between the anode 38 and the control electrode 35 of the repeater device 33 and also certain inherent and undesired capacitive reactance caused by the capacitance between the anode or output circuit and the control-electrode or input circuit comprising the coupling means of this device. Such undesired capacitance is represented by the dotted-line condenser 42. Thus, when the oscillations generated by the oscillator of unit 21, while such oscillator is operating as a superregenerative detector, are applied to the anode 38 of the repeater device 33, the undesirable capacitance 42 tends to produce undesired translation of wave signals from the terminal circuit 26 to the terminal circuit 25 which is in a direction opposite to the direction of normal translation of the repeater device 33.

It is for the purpose of reducing the tendency of a selected repeater device undesirable to translate wave signals in a direction opposite to its direction of normal translation that the tapped winding 32 of the terminal circuit 26 is used and the repeater devices 33 and 34 are coupled to this tapped winding in the manner previously described. Thus, the oscillations generated by the oscillator of unit 21, while such oscillator operates as a superregenerative detector, are not only applied to the anode 38 of the device 33 through the section 32b of the winding 32, but are also applied through the section 32a of this winding and condenser 40 to the control electrode 35' of the repeater device 34. The latter device also has capacitive reactance caused by the inherent capacitance between its anode 38' and its control electrode 35', commonly referred to as "interelectrode capacitance," and capacitive reactance caused by capacitance between its associated coupling means comprising its input and output circuits, such capacitance being represented by the dotted-line condenser 43. Now if the capacitances 42 and 43 are equal, as is generally the case since the repeater devices 33 and 34 are similar and involve similar circuit arrangements, the tap P is made at the center point of the winding 32. In this event, the oscillations which are applied through the capacitance 42 to the terminal circuit 25 from the anode 38 of device 33, under the operating condition assumed, are neutralized by oscillations of equal amplitude but opposite phase applied to the terminal circuit 25 through the capacitance 43 from the control electrode 35' of repeater device 34. These two oscillatory voltages, being of equal amplitude and opposite phase at the input circuit 25, completely neutralize each other and hence no oscillatory voltage is applied to the antenna system 10, 11 for radiation thereby as an undesirable wave

signal which might cause interference with other nearby receivers operating on the same frequency.

Now assume that it is desired to transmit a wave signal generated by the oscillator of unit 21. In that case, the switch 22 is moved to its transmit position T, thereby moving the switch 31 of the translating channel 16 to close its terminal T, thus energizing the cathode circuit of the repeater device 34 and deenergizing that of the repeater device 33. The repeater device 34 of the channel 16 thereupon operates in conventional manner to translate or repeat wave signals applied to the terminal circuit 26 from the oscillator of unit 21, the translated oscillations being applied through the terminal circuit 25 to the antenna system 10, 11 for radiation thereby, the control electrode 35' developing a self-bias potential across the resistor 46 by peak rectification of the applied wave signals. Due to the capacitance 43 of the repeater device 34 and its associated coupling means, a portion of the energy translated to the terminal circuit 25 is fed back to the input circuit of the device 34. Unless the effect of such feed-back energy is neutralized, the repeater device 34 tends to break into sustained oscillation. This is undesirable not only from the standpoint that such oscillations are radiated by the antenna 10, 11 as an undesired spurious wave signal, but also for the reason that the repeater device 34 no longer is capable of translating with fidelity the modulated wave signal. The tendency of the repeater device 34 undesirably to translate such feed-back energy in the direction opposite to the normal direction of translation of energy through this device is reduced by the capacitance 42 of the nonselected repeater device 33 and its associated coupling means. Thus, feed-back energy from the terminal circuit 25 is applied by virtue of the capacitance 43 to the section 32a of winding 32 and feed-back energy of the same magnitude and phase is also applied through the capacitance 42 to the section 32b of winding 32. Now since the magnitude of the amounts of feed-back energy applied to the terminal circuit 26 through the capacitances 42 and 43 are equal and since they are applied with the same phase to opposite sections 32a and 32b of the winding 32, no feed-back energy is applied to the input circuit of the repeater device 34 with the result that there is no tendency of this device to break into sustained oscillation.

Upon selection of the repeater device 34 to translate wave signals from the terminal circuit 26 to the terminal circuit 25, the effective resistance of the tuned circuit 30, 31 is determined in large part by the values of resistance of the input circuit of tube 34 or, in other words, by the value of resistance of the resistor 46 and the resistance between the control electrode 35' and the cathode 36' of tube 34 when the control electrode 35' conducts current. On the other hand, when the repeater device 33 is selectively energized to translate wave signals from the terminal circuit 25 to the terminal circuit 26, the effective resistance of the tuned circuit 30, 31 is determined in large part by the values of resistance of both the input circuit of tube 34 and the output circuit of tube 33. The resistance of the input circuit of tube 34 under this condition comprises only the value of resistance of the resistor 46, since the control electrode 35' no longer conducts current, whereas the resistance of the output circuit of tube 33 comprises the anode-cathode resistance of tube 33.

Now it is known that the resonant frequency of a circuit containing inductance L , capacitance C and resistance R is determined by the relation:

$$f = \frac{1}{2\pi} \sqrt{\frac{1}{LC} - \frac{R^2}{4L^2}} \quad (1)$$

Ordinarily, the value of resistance R in a tuned circuit is not only constant but is small in comparison with the reactive impedance of the tuned-circuit inductor and, as shown by Equation 1, does not play an important part in determining the frequency of the circuit. Where the tuned circuit determines the frequency of generated oscillations, as is the case of the tuned circuit 30, 31 which is the frequency-determining circuit of the oscillator of unit 21, changes of resistance of the tuned circuit may materially affect the frequency of the generated oscillations. In the present arrangement, any change of frequency of the tuned circuit 30, 31, due to selective energization of the repeater devices 33 and 34, is undesirable since such equipments normally are used at least in pairs and, in the event that each unit does not transmit and receive on the same operating frequency, attempts to keep the two units in tune with each other during repeated two-way communications are very likely to result in progressive shift of the operating frequency from an assigned value.

In order, therefore, that the resonant frequency of the tuned circuit 30, 31 shall not vary with selective energization of the devices 33 and 34, it is essential that the effective values of resistance which are coupled into the tuned circuit 30, 31 from the output circuit of the repeater device 33 and the input circuit of the repeater device 34 should be the same regardless of the selective energization of the repeater devices. Now when the repeater device 34 is selectively energized, as by movement of the switch 37 to close its contact T, the resistance coupled into the tuned circuit 30, 31 comprises only the input-circuit resistance of the repeater device 34 which has the value:

$$R_1 = \frac{R_{46} \times R_{sc}}{R_{46} + R_{sc}} \quad (2)$$

where:

R_{46} =the value of resistance of the resistor 46.
 R_{sc} =the effective resistance between the control electrode 35' and cathode 36' of tube 34 when the control electrode conducts current.

It is well known that the effective value of the control electrode-cathode resistance R_{sc} when the tube is operating with peak grid rectification is approximately one-half that of the value of the resistor 46 when the latter is large compared to the ohmic resistance of the space current path. Hence, the input-circuit resistance of tube 34, under this condition of operation, has the value:

$$\frac{R_1 = R_{46}}{3} \quad (3)$$

The value of the resistance coupled into the tuned circuit 30, 31 when the repeater device 33 is selectively energized is given by the relation:

$$R_2 = \frac{R_p \times R_{46}}{R_p + R_{46}} \quad (4)$$

where:

R_p =the anode-cathode or output resistance of repeater device 33 in its conductive state.

Now if the effective value of resistance R_1 75

coupled into the tuned circuit 30, 31 when the repeater device 34 is energized is equal to the effective value of resistance R_2 which is coupled into the tuned circuit 30, 31 when the repeater device 33 is energized, the resonant frequency of the tuned circuit 30, 31 is not changed by the selective energization of the repeater devices 33, 34. This is most readily accomplished by proportioning the value of the resistor 46 with relation to the anode-cathode resistance of the repeater device 33. The value of the resistor 46 which satisfies the required conditions is found from the solution of Equations 3 and 4 and is:

$$R_{46} = 2R_p \quad (5)$$

In this manner the impedance values of the input circuit parameters of repeater device 34 are so proportioned with relation to the impedance values of the output circuit of the parameters of the other repeater device 33 in its conductive state that the resonant frequency of the tuned circuit 30, 31 is substantially constant with selective energization of the devices 33 and 34.

In the event that the repeater devices 33 and 34 are not similar, whereby the values of the capacitances 42 and 43 are not equal, the point at which the tap P is made on the winding 32 of the terminal circuit 26, is adjusted accordingly to insure that any wave-signal voltage translated from one terminal circuit to the other through the inherent capacitance of a selected device has a magnitude at such other terminal circuit equal to the same wave-signal voltage translated through the nonselected device. Thus, if the capacitance 43 is larger than the capacitance 42, the tap P will be made on the winding 32 at such point that the section 32a is proportionally smaller than the section 32b. Should the tap P be changed to a point on the winding 32 other than the central point thereof, the value of resistor 46 likewise must be modified to insure that the effective resistance which is coupled into the tuned circuit 30, 31 shall be constant regardless of the selective energization of the repeater devices 33 and 34. The new value which the resistor 46 should have in this event may readily be determined from the principles given above.

From the above description of the invention, it will be evident that the wave-signal translating channel 16 includes means for reducing the tendency of a selected repeater device undesirably to translate wave signals in the direction opposite to the selected direction comprising means including the undesirable reactance of the non-selected one of the devices and its associated coupling means for neutralizing the undesirable reactance of the selected device and its associated coupling means. The last-named means includes the tapped winding 32 of the terminal circuit 26, this tapped winding being effective to translate in the direction opposite to the selected direction wave signals having equal amplitude but opposite phase to the wave signals undesirably translated in the said opposite direction by the selected repeater device. Consequently, the neutralizing means includes a connection of the output electrodes of one of the devices across one section of the tapped winding and a connection of the input electrodes of the other device across the other section of the tapped winding.

While in the arrangement described the means for selectively energizing the repeater devices 33 and 34 comprises the switch 37, it will be evident that other means of selective energization may be employed. For example, selective values of

bias may be applied to the control electrodes 35 and 35' of the respective repeater devices 33 and 34 by which to control these devices in the manner and for the purpose described.

There occurs a very slight change in the inter-electrode capacitance of the repeater devices 33 and 34 when the energization of these devices is changed. In the event that such change of capacitance in a particular application prevents exact neutralization for both directions of translation of wave signals for a given point at which the tap P is made on the winding 32, exact neutralization may nevertheless be effected either by making the tap P adjustable on the winding 32 and by mechanically connecting the tap for unicontrol operation with the switches 22 and 37, or by letting the tap P remain fixed and by using one or more condensers of small capacitance which are selectively connected in shunt to one or both of the capacitances 42 and 43 by a suitable switch operated in unicontrol with the switch 37.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A wave-signal translating channel comprising, a pair of terminal circuits for said channel, a pair of vacuum-tube repeater devices, means for coupling said devices between said terminal circuits to effect translation of wave signals between said terminal circuits in one direction through one of said devices and in an opposite direction through the other of said devices, each of said devices and its associated coupling means having undesirable reactance tending to produce undesirable translation of wave signals between said terminal circuits in a direction opposite to its direction of normal translation, means for selectively energizing said repeater devices to effect translation of wave signals in a selected direction between said terminal circuits, and means for reducing the tendency of a selected device undesirably to translate wave signals in the direction opposite to said selected direction comprising means including the undesirable reactance of the nonselected one of said devices and its associated coupling means for neutralizing the undesirable reactance of said selected device and its associated coupling means.

2. A wave-signal translating channel comprising, a pair of terminal circuits for said channel, a pair of vacuum-tube repeater devices, means for coupling said devices between said terminal circuits to effect translation of wave signals between said terminal circuits in one direction through one of said devices and in an opposite direction through the other of said devices, each of said devices and its associated coupling means having undesirable capacitive reactance tending to produce undesirable translation of wave signals between said terminal circuits in a direction opposite to its direction of normal translation, means for selectively energizing said repeater devices to effect translation of wave signals in a selected direction between said terminal circuits, and means for reducing the tendency of a selected device undesirably to translate wave signals in the direction opposite to said selected direction

comprising means including the undesirable capacitive reactance of the nonselected one of said devices and its associated coupling means for neutralizing the undesirable capacitive reactance of said selected device and its associated coupling means.

3. A wave-signal translating channel comprising, a pair of terminal circuits for said channel, a pair of vacuum-tube repeater devices, means for coupling said devices between said terminal circuits to effect translation of wave signals between said terminal circuits in one direction through one of said devices and in an opposite direction through the other of said devices, each of said devices having inherent interelectrode capacitance tending to produce undesirable translation of wave signals between said terminal circuits in a direction opposite to its direction of normal translation, means for selectively energizing said repeater devices to effect translation of wave signals in a selected direction between said terminal circuits, and means for reducing the tendency of a selected device undesirably to translate wave signals in the direction opposite to said selected direction comprising means including the inherent capacitance of the nonselected one of said devices for neutralizing the inherent capacitance of said selected device.

4. A wave-signal translating channel comprising, a pair of terminal circuits for said channel, a pair of vacuum-tube repeater devices, means for coupling said devices between said terminal circuits to effect translation of wave signals between said terminal circuits in one direction through one of said devices and in an opposite direction through the other of said devices, each of said devices and its associated coupling means having undesirable reactance tending to produce undesirable translation of wave signals between said terminal circuits in a direction opposite to its direction of normal translation, means for selectively energizing said repeater devices to effect translation of wave signals in a selected direction between said terminal circuits, and means for reducing the tendency of a selected device undesirably to translate wave signals in the direction opposite to said selected direction comprising means including undesirable reactance of the nonselected one of said devices and its associated coupling means for translating in said direction opposite to said selected direction wave signals having equal amplitude but opposite phase to the wave signals undesirably translated in said opposite direction by said selected device.

5. A wave-signal translating channel comprising, a pair of terminal circuits for said channel, one of said terminal circuits including a tapped winding, a pair of vacuum-tube repeater devices, means for coupling said devices between said terminal circuits to effect translation of wave signals between said terminal circuits in one direction through one of said devices and in an opposite direction through the other of said devices, each of said devices and its associated coupling means having undesirable reactance tending to produce undesirable translation of wave signals between said terminal circuits in a direction opposite to its direction of normal translation, means for selectively energizing said repeater devices to effect translation of wave signals in a selected direction between said terminal circuits, and means for reducing the tendency of a selected device undesirably to translate wave signals in the direction opposite to said selected direction comprising means including said tapped

winding and the undesirable reactance of the nonselected one of said devices and its associated coupling means for neutralizing the undesirable reactance of said selected device and its associated coupling means.

6. A wave-signal translating channel comprising, a pair of terminal circuits for said channel, one of said terminal circuits including a tapped winding providing a winding section on each side of said tap, a pair of vacuum-tube repeater devices each including input and output electrodes, means for coupling said devices between said terminal circuits to effect translation of wave signals between said terminal circuits in one direction through one of said devices and in an opposite direction through the other of said devices, each of said devices and its associated coupling means having undesirable reactance tending to produce undesirable translation of wave signals between said terminal circuits in a direction opposite to its direction of normal translation, means for selectively energizing said repeater devices to effect translation of wave signals in a selected direction between said terminal circuits, and means for reducing the tendency of a selected device undesirably to translate wave signals in the direction opposite to said selected direction comprising means including the undesirable reactance of the nonselected one of said devices and its associated coupling means for neutralizing the undesirable reactance of said selected device and its associated coupling means, said last-named means including a connection of the output electrodes of one of said devices across one section of said tapped winding and a connection of the input electrodes of the other device across the other section of said tapped winding.

7. A wave-signal translating channel comprising, a pair of terminal circuits for said channel, a pair of vacuum-tube repeater devices each including a cathode circuit, means for coupling said devices between said terminal circuits to effect translation of wave signals between said terminal circuits in one direction through one of said devices and in an opposite direction through the other of said devices, each of said devices and its associated coupling means having undesirable reactance tending to produce undesirable translation of wave signals between said terminal circuits in a direction opposite to its direction of normal translation, means for selectively energizing the cathode circuits of said repeater devices to effect translation of wave signals in a selected direction between said terminal circuits, and means for reducing the tendency of a selected device undesirably to translate wave signals in the direction opposite to said selected direction comprising means including the undesirable reactance of the nonselected one of said devices and its associated coupling means for neutralizing the undesirable reactance of said selected device and its associated coupling means.

8. A wave-signal translating channel comprising, a pair of terminal circuits for said channel,

a pair of vacuum-tube repeater devices each including input and output electrodes coupling said terminal circuits to effect translation of wave signals therebetween in one direction through one of said devices and in an opposite direction through the other of said devices in accordance with selective energization of said repeater devices, a resonant circuit included in said channel and tuned to a selected operating frequency, the input electrodes of one of said devices and the output electrodes of the other of said devices being coupled to said resonant circuit, the impedance values of the input circuit parameters of said one device being so proportioned with relation to the impedance values of the output circuit parameters of said other device in its conductive state that the resonant frequency of said tuned circuit is substantially constant with selective energization of said devices.

9. A wave-signal translating channel comprising, a pair of terminal circuits for said channel, a pair of vacuum-tube repeater devices each including input and output electrodes coupling said terminal circuits to effect translation of wave signals therebetween in one direction through one of said devices and in an opposite direction through the other of said devices in accordance with selective energization of said repeater devices, a resonant circuit included in said channel and tuned to a selected operating frequency, the input electrodes of one of said devices and the output electrodes of the other of said devices being coupled to said resonant circuit, a resistor connected across the input electrodes of said one device, the value of said resistor being so proportioned with relation to the impedance values of the output circuit parameters of said other device in its conductive state that the resonant frequency of said tuned circuit is substantially constant with selective energization of said devices.

10. A wave-signal translating channel comprising, a pair of terminal circuits for said channel, a pair of vacuum-tube repeater devices each including input and output electrodes coupling said terminal circuits to effect translation of wave signals therebetween in one direction through one of said devices and in an opposite direction through the other of said devices in accordance with selective energization of said repeater devices, a resonant circuit included in said channel and tuned to a selected operating frequency, the input electrodes of one of said devices and the output electrodes of the other of said devices being coupled to said resonant circuit, the output circuit of said other device in its conductive state having a predetermined value of resistance, and a resistor connected across the input electrodes of said one device and having a value of resistance approximately twice that of the output circuit of said other device to maintain the resonant frequency of said tuned circuit substantially constant with selective energization of said devices.

NELSON P. CASE.
